US00D943907S

(12) **United States Design Patent** (10) **Patent No.:** **US D943,907 S**
(45) **Date of Patent:** **** Feb. 22, 2022**

(54) **SHOE**

(71) Applicant: **Cole Haan LLC**, Greenland, NH (US)

(72) Inventors: **Pablo Chao**, Greenland, NH (US);
Kyle Jenkins, Greenland, NH (US)

(73) Assignee: **COLE HAAN LLC**, Greenland, NH
(US)

(**) Term: **15 Years**

(21) Appl. No.: **29/721,491**

(22) Filed: **Jan. 21, 2020**

(51) LOC (13) Cl. **02-04**

(52) U.S. Cl.

(57) **CLAIM**

The ornamental design for a shoe, as shown and described.

DESCRIPTION

FIG. 1 is a first perspective view of a shoe showing our new design;
FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dot-dash lines immediately adjacent the shaded areas represent the bounds of the claimed design while all other broken lines illustrate portions of the shoe that form no part of the claimed design.

1 Claim, 7 Drawing Sheets
